UNITED STATES PATENT OFFICE.

HERBERT P. MILKER, OF BROOKLYN, NEW YORK, ASSIGNOR TO CHARLES J. TAGLIABUE MANUFACTURING CO., OF BROOKLYN, NEW YORK, A CORPORATION OF NEW YORK.

THERMOMETER.

Application filed July 26, 1919. Serial No. 313,558.

To all whom it may concern:

Be it known that I, HERBERT P. MILKER, a citizen of the United States, and resident of the borough of Brooklyn, county of 5 Kings, city and State of New York, have invented certain new and useful Improvements in Thermometers, of which the following is a specification.

My invention relates to thermometers and 10 has for its object the provision of an efficient and serviceable thermometer which may be produced at a minimum cost and which in its finished form presents an attractive and pleasing appearance. Other more specific 15 objects will appear from the description hereinafter and the features of novelty will be pointed out in the appended claims.

In the accompanying drawings which, without defining the limits of the invention, 20 illustrate a specific embodiment thereof. Fig. 1 is a front elevation of the thermometer; Fig. 2 is a rear elevation; and Fig. 3 is a side view thereof.

In the illustrated form the thermometer 25 comprises a back 5 which is constructed of pasteboard or other similar cheap material and has its front face suitably embellished or ornamented to present an attractive appearance. For instance, said front face may 30 be covered with what is commonly known as Japanese wood veneer to give to the back the appearance of being made of finely grained wood or said front face may be otherwise treated to simulate other materials as desired. A suitable scale 6 is produced upon the front face of said back 5 in any suitable manner and in proper co-operative relation to the usual tube 7 which terminates at one end in the customary bulb 35 8 and is fastened to the back 5 in any convenient way as by means of wires 9 which pass around said tube and through the back and have their ends twisted together as shown in Fig. 2.

40 Because of the fact that the pasteboard or other cheap material of which the back 5 is constructed has very little inherent rigidity of its own, said back is easily bent, flexed and even broken transversely of its length 45 and thus by itself affords little protection to the tube 7 against being snapped or broken in two. In other words, a bending or breaking of the back 5 will, unless provision is made to obviate this contingency, fracture

the tube 7 for instance at some point between 55 the fastening wires 9. To overcome this danger and to prevent the transverse flexing and breaking of the back or in other words to stiffen the same, a stiffening device is provided preferably so as to be, for at least the 60 major part, invisible from the front of the thermometer. In the illustrated example this stiffening device comprises a wire 10 which extends lengthwise of the back 5 in surface contact with the rear face thereof 65 and is bent into zig-zag or equivalent form at an intermediate point as indicated at 11, to include within its stiffening effect, a maximum area of the back 5 at the region where 70 its tendency to bend and break is greatest. The stiffening wire 10 is preferably secured in place by the fastening wires 9 which pass about the same as shown in Fig. 2 and in such case, in addition to its other functions, 75 serves to prevent said wires 9 from being pulled or torn through the back 5, and at the same time makes unnecessary the use of separate means for accomplishing this purpose. The section 11 of the stiffening device 80 10, by reason of its form, prevents the wire 10 from turning about its axis and becoming displaced relatively to the back and thereby producing a strain upon the fastening wires 9 tending to loosen the same.

As shown in the drawings, the stiffening 85 device 10 is preferably continued at its one end, beyond the back 5, in the form of an eyelet 12 whereby said thermometer may be suspended, and whereby the necessity for a separate fastening device is obviated. At its 90 other end said device or wire 10 is preferably bent over the edge of the back 5 to form a recess 13 for the accommodation thereof and preferably continued in the form of an upwardly protecting guard 14 located in the 95 front of and in registry with the bulb 8 of the tube 7 which is thus protected, in the usual manner, against injury and whereby the necessity for a separate guard for this purpose, is done away with.

100 The thermometer in its illustrated form is reduced to the utmost simplicity and requires in its construction only such materials as are readily obtained and which are low in cost so that it is economical to produce 105 and may be sold at an extremely low price. At the same time the thermometer is efficient in operation and presents a highly at-

tractive appearance far beyond anything suggested by the cost at which it may be produced and purchased.

The back 5 instead of being made of pasteboard may be constructed of any other fibrous material or of any other suitable substance which is cheap and the inherent resistance of which against bending, or flexing, or even against actual breakage, is relatively slight.

While the device 10 is intended primarily for combination with backs 5 of the type described to stiffen the same, said device in addition constitutes a combined suspending device whereby the thermometer may be efficiently suspended and a bulb guard whereby the guard of the bulb of the thermometer tube is efficiently protected against injury. In this sense, said device may be readily and easily combined with backs having sufficient inherent rigidity of their own to make the stiffening function of the device unnecessary or secondary and to make it useful simply as a suspending device and a bulb guard. In other words, in addition to its other functions, said device may be utilized advantageously as a combined suspending device and bulb guard and for this purpose may be combined with any type of back.

Various changes in the specific form shown and described may be made within the scope of the claims without departing from the spirit of my invention.

35 I claim:

1. A thermometer comprising a back of pasteboard, a thermometer tube upon one face thereof, means passing through said back for securing said tube in position 40 therein and a stiffening device whereby said back is stiffened against flexing and whereby said tube fastening means are prevented from being torn out of said back.

2. A thermometer comprising a back capable of being readily flexed, a thermometer tube terminating at one end in a bulb and secured upon said back, a stiffening device extending lengthwise of the rear surface of said back to stiffen the same against flexing, 50 a suspending device located beyond one end of said back and comprising an integral continuation of said stiffening device at one end and a bulb guard located in registry with said bulb and comprising an integral continuation of said stiffening device at the other end.

3. A thermometer comprising a back capable of being readily flexed, a thermometer tube extending lengthwise of the front 60 face of said back, a stiffening wire ex-

tending lengthwise of the rear surface thereof to stiffen said back against flexing, said wire extending transversely of its length in opposite directions at an intermediate point to include a maximum area 65 of said back within its stiffening effect, an eyelet located beyond one end of said back and comprising an integral extension of said stiffening wire; a bulb guard located in registry with said bulb and comprising an 70 integral forward and upward extension of said stiffening wire and fastening devices passing about said tube through said back and about said stiffening wire to secure the latter and said tube in position on said back 75 and to be held thereby against tearing through the latter.

4. A thermometer comprising a back, a tube extending lengthwise of said back and terminating at one end in a bulb, a device 80 comprising an element separate from said back and constituting a suspending member at one end and a bulb guard at the other end, said member and guard forming integral continuations of each other, and means for 85 fastening said device to said back.

5. A thermometer comprising a back, a tube extending lengthwise of the front face of said back and terminating at one end in a bulb and a member secured to the rear face 90 of said back and extending lengthwise and beyond one end thereof to form a suspending device, said member, at its other end, being provided with a return member forming a recess for the reception of said back 95 and projecting over the front face thereof to form a bulb guard.

6. A thermometer comprising a back capable of being readily flexed, a thermometer tube secured upon said back and a stiffening 100 wire extending lengthwise of said back to stiffen the same against flexing, said wire having a zig-zag intermediate portion projecting transversely beyond its major axis in opposite directions to include a maximum 105 area of said back within its stiffening effect.

7. A thermometer comprising a sheet-like back capable of being readily flexed, a thermometer tube terminating at one end in a bulb and secured upon the front surface of 110 said back, a stiffening wire extending lengthwise of the rear surface of said back to stiffen the same against flexing and a bulb guard comprising an integral continuation of said stiffening wire at its lower end and 115 projecting upwardly in front of said back in registry with said bulb.

In testimony whereof I have hereunto set my hand.

HERBERT P. MILKER.
